UNITED STATES PATENT OFFICE.

ALOIS GASCHLER, OF BERLIN, GERMANY.

METHOD OF ARTIFICIALLY PRODUCING RADIOACTIVE SUBSTANCES.

Application filed September 4, 1924, Serial No. 735,962, and in Germany April 20, 1923.

The object of this invention is to transform materials of relatively low radioactivity into materials of relatively high radioactivity and in general to increase the radioactivity of such materials.

Another object of my invention is to increase the radioactivity of uranium and thorium.

Another object of my invention is to accelerate to a high degree the very slow spontaneous transformation of uranium and thorium.

In general, in the process of my invention, a small quantity of metal to be transformed is heated to a high temperature under high pressure in an enclosed chamber. The metallic vapor is dissociated, and is exposed either to high electro-static, uni-directional potentials or to uni-directional currents at high potentials. The volume of the chamber is usually large in proportion to the normal volume of the material to be transformed. The currents and high potentials may be employed concurrent with the heating step. I have used on the average approximately 100 kilowatt seconds of electrical energy to produce 1 gram of uranium or thorium.

In order to produce a very high pressure, while heating the metal and to avoid as much as possible the loss of energy by the escape of heat, such as radiation, the metal is formed into a thin filament weighing about 1 gram. The filament is fixed inside a channel formed in a mass of insulating material, such as massive quartz, granite, steatite or other stone or mineral. The two ends of the filament are attached to two large metallic disks which act also as closing means for the channel. These disks bear clamps to which leads for the source of current may be attached. The duration of the current is usually 1-2 seconds. After cooling the metal may be regained either by mechanical or chemical means.

Tested by different methods the product obtained proves to be considerably more radioactive than the product before transformation. This process can also be applied to the rational transformation of other elements.

The efficiency of the transformation is all the greater the higher the potential of the current. The efficiency is also higher, the more the dissociated vapor comes in contact with the pole faces. In operating this process it is advisable therefore to employ not

only a heating current of low voltage and high intensity but also a current of small intensity and high voltage. It is therefore advisable to insert into the chamber a second pair of electrodes of large surface which is connected to a high tension circuit. A Crooks tube and a rectifier tube may be employed in this circuit as a high tension resistance.

In operating on a large scale, instead of using metallic filaments, the metal to be transformed is introduced into the chamber containing the electric arc via a valve and is also removed from this chamber via a valve.

Reference may be had to the accompanying figure for an apparatus capable of carrying out my process.

Referring to this drawing, *a* is an earthenware jacket or sheathing, in which there is provided a cavity or hollow space *b* for the reception of the metal to be transformed which metal passes through the cavity *b* in the form of a filament *c* or, if mercury is involved, fills the passage *b* so as to form a continuous conductor from the one metal plate *d* to the other metal plate *e*. These two metal plates *d* and *e* are fitted with the necessary current terminals.

The above is to be taken as merely illustrative of my invention and the best mode of operating the same and not as limiting the invention which is defined in the appended claims.

1. A process for increasing the radioactivity of materials which comprises heating the same to a high temperature and pressure and submitting the heated material to the influence of a high potential current.

2. A process for increasing the radioactivity of materials which comprises heating the same to a high temperature and pressure in a relatively large chamber and submitting the said material to a high potential uni-directional current.

3. A process for increasing the radioactivity of materials which comprises heating said materials to a high temperature by means of an electric current of low voltage and high intensity and subjecting said heated materials to a current of high voltage and low intensity.

4. A process for increasing the radioactivity of materials which comprises heating said materials to a high temperature to vaporize said material and submitting said vapors to the action of a high tension cur-

rent passing between electrodes of relatively large electrode surfaces and submitting said vapors to contact with said electrodes.

5. A process for the increasing radioactivity of materials which comprises vaporizing said materials by heating said materials to a high temperature and at a high pressure by

means of a current of low voltage and high intensity and submitting said vapors to contact with relatively large electrodes and passing a high tension low intensity current between said electrodes. 10

In testimony whereof I affix my signature.
DR. ALOIS GASCHLER.
